CLAIM

The ornamental design for a multiple compartment waste container, as shown and described.

DESCRIPTION

FIG. 1 is a front elevational view of a multiple compartment waste container showing my new design;

FIG. 2 is a top plan view thereof;

FIG. 3 is a left side elevational view thereof, the right side view being a mirror image of that shown;

FIG. 4 is a bottom plan view thereof; and

FIG. 5 is a rear elevational view thereof.

FIG. 1

FIG. 2

FIG. 3

FIG. 4

FIG. 5
